SOAP TRAY

John J. Russell, Bellerose, N. Y.

Application April 22, 1954, Serial No. 30,131

Term of patent 14 years

(Cl. D4—3)

Fig. 1.

Fig. 2.

Fig. 3.

Fig. 4.

To all whom it may concern:

Be it known that I, John J. Russell, a citizen of the United States, residing at Bellerose, in the county of Nassau and State of New York, have invented a new, original, and ornamental Design for a Soap Tray, of which the following is a specification, reference being had to the accompanying drawing, forming part thereof.

Fig. 1 is a plan view of a soap tray embodying my new design.

Fig. 2 is a front view thereof.

Fig. 3 is a end view thereof.

Fig. 4 is an isometric view of said tray.

I claim:

The ornamental design for a soap tray, substantially as shown.
